UNITED STATES PATENT OFFICE

LEWIS J. BAZZONI, OF SWAMPSOFT, MASSACHUSETTS, ASSIGNOR TO UNITED SHOE MACHINERY CORPORATION, OF PATERSON, NEW JERSEY, A CORPORATION OF NEW JERSEY

HEEL COVER TUCKING MACHINE

Application filed January 4, 1930. Serial No. 418,641.

This invention relates to cover tucking apparatus, and is herein exemplified as embodied in a machine for tucking the edge portion of a heel cover into a channel in a heel 5 of a type which has come into use in recent years.

It is an object of the invention to provide an improved cover tucking apparatus which, while simple in construction, will be easy to 10 operate and capable of tucking heel covers into channelled heels very rapidly and smoothly.

With this object in view, an important feature of the invention consists in the combination with a stepped tucking tool of means for imparting to said tool a tucking movement which is preferably, although not necessarily, a rocking movement. Such a tool may comprise a blade having a stepped edge and is 15 adapted to be operated in such a manner as to force cover material more and more deeply into a heel channel in a succession of stages, whereby the tucking operation may be performed with a minimum of effort or force and 20 with a minimum of strain upon the cover material. In order to promote rapidity of operation the tucking tool may be kept in continual movement and, in this connection, invention is to be recognized in a machine having 25 provision for imparting continual rocking movement to a cover tucking tool, whether the tool be stepped or not.

A still further feature of the invention resides in the combination with a cover tucking tool of means for imparting to said tool a rocking movement about a point in its tucking portion. In the case of a tool comprising a stepped blade the rocking movement 30 would preferably occur about a point substantially in the stepped portion of the blade.

In the illustrated machine the tucking tool is mounted upon the end of a rock shaft which may derive movement, for example, from a drive shaft through suitable power transmitting connections, shown herein as comprising a crank upon the drive shaft co-operating with a slotted rocker member upon the rock shaft to impart continual rocking movement 45 to the latter.

These and other features and advantages of

the invention will be better understood and appreciated from reading the following detailed description of one embodiment thereof in connection with the accompanying drawings, in which

55

Fig. 1 is a view in side elevation, partly in section, of a machine embodying the invention;

Fig. 2 is a sectional detail view on the line II—II of Fig. 1, showing the means for imparting rocking movement to the tucking tool;

Fig. 3 is a view in front elevation, showing the tucking tool and the manner in which it operates in the channel in the heel; and

65

Fig. 4 is a perspective view, showing the manner in which the work is presented to the machine and operated upon.

In the drawings 10 indicates a suitable base or frame in and upon which the working parts 70 of the machine are supported. Suitably journaled in the frame 10 is a continually rotating drive shaft 12 carrying a crank disk 14 in which is secured a crank pin 16, eccentric to the axis of the shaft 12. Loosely engaged by the crank pin 16 is a block 18 adapted to slide in a slot 20 formed in a rocket member 22 which is rigidly secured to a rock shaft 24, also journaled in the frame 10.

At the right-hand end of the rock shaft 80 24, as viewed in Fig. 1, there is provided an upwardly bent rocker arm 26 to which is secured, by a screw 28, a tucking tool 30 comprising a thin blade of peculiar formation in that the portion of its edge which engages the heel cover material and tucks it into the channel in the heel is stepped, as shown at 32 in Figs. 3 and 4.

It will be apparent that rotation of the 90 shaft 12 in either direction will impart a continual rocking movement to the rock shaft 24, including the rocker arm 26 which carries the tucking blade 30, the arrangement being such that a point substantially in the 95 stepped edge portion of the blade, at or near its lower end, lies in the axis of the rock shaft, as a consequence of which a continual rocking movement about the said point is imparted to the tucking blade. This is well shown in 100

Fig. 3 wherein the dotted lines represent one of the extreme positions of the blade.

Accurate presentation of the heel to the machine is facilitated by side and breast gages shown in Figs. 1 and 4 wherein 34 indicates a side gage having a heel engaging face 36 which is curved to an approximation of the average curvature of the heel to be operated upon. The gage 34 is sustained by a vertically adjustable upright 38 provided with a slot 40 through which passes a clamping screw 42 threaded into a horizontally adjustable carrier 44. Adjustment of the carrier 44 is provided for by a screw 46 having 10 threaded engagement with a flange or web 48 of the machine frame 10 and swiveled engagement with the carrier, as shown at 50. A clamping bolt 52, passing through a slot 54 in the carrier, provides for securing the carrier firmly in any position to which it may be adjusted.

The breast gage comprises a disk 56 which also constitutes a guard for the tucking blade. The said disk is freely rotatable upon a stationary pin 58 screwed into an overhanging arm 60 which is bolted adjustably to an upright 62 arising from the frame 10.

A channeled heel to which covering material is to be applied is illustrated at 64, the 30 channel in the heel into which the covering material is to be tucked being shown at 66 and the side and breast covers for the heel being shown at 68 and 70 respectively.

The heel covering material is applied 35 smoothly to the heel with the marginal portions of the cover overlying the channels in the heel as shown at the left in Fig. 4. The shaft 12 rotates at high speed and a continual high speed rocking movement is, therefore, 40 imparted to the tucking tool 30. The heel with the applied cover is presented to the rocking tucking blade, the gages 34 and 56 being so adjusted as to facilitate the positioning of the heel to cause the point of the blade 45 to enter the channel 66 and acting to steady and guide the heel. The stepped formation causes the tool to force the cover material more and more deeply into the channel in successive stages as the tool is rocked and 50 this stepped progressive tucking action continues from one end of the channel to the other as the heel is moved lengthwise along the face 36 of the side gage 34, until the tucking is complete.

55 The rapidly rocking tool operates to tuck the heel cover into the channel in the heel rapidly and smoothly, the stepped formation of the tucking blade not only making the operation very easy, but overcoming any 60 tendency of the tool to crowd the cover material ahead of it and form wrinkles in said material.

Having described the invention, what is claimed as new and desired to be secured by 65 Letters Patent is:

1. In a heel covering machine, the combination of a stepped tucking tool and means for imparting tucking movement to said tool.

2. In a cover tucking machine, the combination of a stepped tucking tool and means 70 for imparting rocking movement to said tool.

3. In a cover tucking machine, the combination of a tucking tool and means for imparting continual rocking movement to said tool.

4. In a cover tucking machine, the combination of a stepped tucking tool and means 75 for imparting continual rocking movement to said tool.

5. In a cover tucking machine, the combination of a tucking tool and means for imparting to said tool movement about a point in its tucking portion.

6. In a cover tucking machine, the combination of a tucking tool and means for imparting to said tool rocking movement about a point in its tucking portion.

7. In a cover tucking machine, the combination of a tucking tool and means for imparting to said tool continual rocking movement about a point in its tucking portion.

8. In a cover tucking machine, the combination of a tucking tool comprising a blade having a stepped edge and means for imparting to said tool rocking movement about a 95 point substantially in said stepped edge.

9. In a cover tucking machine, the combination of a rockshaft, a tucking tool mounted upon the end of said shaft, and means for imparting rocking movement to said shaft.

10. In a cover tucking machine, the combination of a continually driven rock shaft and a stepped tucking blade mounted upon the end thereof.

11. In a cover tucking machine, the combination of a rotating drive shaft, a rock shaft, power transmitting connections between the drive shaft and the rock shaft, and a tucking tool mounted upon the rock shaft.

12. In a cover tucking machine, the combination of a rock shaft and a tucking blade having a stepped edge mounted upon said shaft, the axis of the shaft passing substantially through said stepped edge.

13. In a cover tucking machine, the combination of a rotating drive shaft, a rock shaft, a slotted rocker member upon the rock shaft, a crank upon the drive shaft co-operating with said member to impart continual rocking movement to the rock shaft, and a 115 tucking tool mounted upon the rock shaft.

In testimony whereof I have signed my name to this specification.

LEWIS J. BAZZONI.
